(57) **CLAIM**

I claim the ornamental design for a dispenser, as shown and described.

DESCRIPTION

FIG. 1 is perspective view of a first embodiment of the dispenser which is a translucent dispenser showing my new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is perspective view of a second embodiment of the dispenser which is a white dispenser showing my new design;

FIG. 9 is a front view thereof;

FIG. 10 is a back view thereof;

FIG. 11 is a right side view thereof;

FIG. 12 is a left side view thereof;

FIG. 13 is a top view thereof;

FIG. 14 is a bottom view thereof;

FIG. 15 is perspective view of a third embodiment of the dispenser which is a black and white dispenser (black back and white front) showing my new design;

FIG. 16 is a front view thereof;

FIG. 17 is a back view thereof;

FIG. 18 is a right side view thereof;

FIG. 19 is a left side view thereof;

FIG. 20 is a top view thereof;

FIG. 21 is a bottom view thereof;

FIG. 22 is perspective view of a fourth embodiment of the dispenser which is a translucent and white dispenser (translucent back and white front) showing my new design;

FIG. 23 is a front view thereof;

FIG. 24 is a back view thereof;

FIG. 25 is a right side view thereof;

FIG. 26 is a left side view thereof;

FIG. 27 is a top view thereof; and,

FIG. 28 is a bottom view thereof.

The broken line in the figure drawings represents unclaimed environment only and forms no part of the claimed design.
